UNITED STATES PATENT OFFICE

155,489

DESIGN FOR A TOILET BOWL CLEANER

Edwin B. de Mesquita, Jamaica, N. Y., assignor to American Safety Razor Corporation, Brooklyn, N. Y., a corporation of Virginia

Application December 13, 1947, Serial No. 143,129

Term of patent 3½ years

(Cl. D9—2)

To all whom it may concern:

Be it known that I, Edwin B. de Mesquita, a citizen of the United States and a resident of Jamaica, Long Island, county of Queens, and State of New York, have invented a new, original, and ornamental Design for a Toilet Bowl Cleaner, of which the following is a specification, reference being had to the accompanying drawing, forming part thereof.

The figure is a front elevational view of a toilet bowl cleaner showing my new design.

I claim:

The ornamental design for a toilet bowl cleaner, as shown.

EDWIN B. DE MESQUITA.
